BOOT, ETC.

John F. Sapluk, Seymour, Conn.

Application November 5, 1930. Serial No. 483,495

2 Claims. (Cl. 36—45)

- This invention relates to boots and puttees, or other foot wear having a body or upper extending well above the calf and close to the knee of the wearer.
- 5 Foot wear of this kind as made heretofore was arranged so that the foot could be inserted through the open upper end, and this required the body to be considerably over-size at various portions to enable the foot to enter and be turned 10 into the bottom portion of the boot. This resulted in such articles being more or less clumsy in appearance, while their use was an endeavor on the part of the wearer, aside from the strictly utilitarian purpose, to appear trim and chic. This 15 is particularly true of "Russian" boots and riding boots.
- An object of the present invention is to provide a fitted boot, that is to say, a boot which actually fits the leg of the wearer, being properly 20 shaped to neatly encase the calf and gradually tapering to snugly fit the ankle, so that no more room is left within the boot than is necessary for the comfort of the wearer.
- This is accomplished by the present invention 25 in its preferred form, by cutting the leather, or other material of which the boot is made, to the pattern of the leg of the wearer, leaving the back of the boot open from top to bottom, and by providing for closing this opening by an interlocking 30 fastening device, the latter extending down close enough to the heel to permit the wearer's foot to be slid into the foot-receiving portion of the boot.
- A further feature of this invention is the provision of a fly extending for the length of the interlocking device and adapted to conceal it 35 from view, this fly being held in place by snap fasteners or the like.
- The present invention also embraces the provision of the arrangement above described for puttees or leg protectors, which are not provided with a shoe portion. And, in this case, the article may be unslit at its upper end and open 40 at its lower end, for with the open back the shoe-clad foot of the wearer may be inserted through the top opening without inconvenience.
- 45 Other features and advantages will hereinafter appear.
- 50 In the accompanying drawing—
- Figure 1 is a side elevation of a boot made in accordance with this invention.
- Fig. 2 is a rear elevation with the boot partially closed.
- 55 Fig. 3 is a rear elevation with the boot com-
- pletely closed and a concealing flap secured in place.
- Fig. 4 is a blank of the upper and heel portion of the boot.
- Fig. 5 is a rear view of the lower portion of 60 the boot, showing the boot completely open.
- Fig. 6 is a transverse sectional view taken on the line 6—6 of Fig. 1.
- Fig. 7 is a perspective view of a puttee made in accordance with the present invention. 65
- The boot shown in the accompanying drawing as exemplary of the present invention, has a sole 10, a heel 11, a combined vamp and upper 12, which is made of one piece of leather and a leg-encircling part 13 sewed to the member 12, and 70 at the rear having a heel portion 14.
- In accordance with the present invention, the leg-encircling part 13 is fitted to the leg of the wearer, having its upper end 15 snugly fitting the leg just above the calf, the portion 16 below this 75 enlarged to fit the calf, and from this portion 16 the body tapers down fitting the leg of the wearer to the narrow ankle portion 17.
- The leg-encircling part 13 is formed from a blank 13a, shown in Fig. 4, which is cut to fit the 80 leg of the wearer when the edges 18 are brought together, so as to fit snugly the leg of the wearer without discomfort. The blank is suitably reinforced or stiffened to maintain its shape. Clearly, 85 with such a fitted boot, and with the edges 18 of the leg-encircling part 13 sewed, or otherwise permanently secured together, it would be impossible to insert the foot into the part 12 of the boot.
- In boots of this general type as previously made, 90 the portions 15 and 17 of the leg-encircling part 13 had to be made over-size so that the foot could be inserted and turned to enter the part 12 of the boot. This over-size angle and upper portion, 95 while being a necessary evil, did not enhance the appearance of the article, and in fact, the wrinkles which would result from such over-sized portions detracted from the appearance of the wearer instead of enhancing it.
- To permit such a fitted boot to be made, the leg- 100 encircling part 13 of the boot is, according to the present invention, not permanently secured together, and instead of a back seam, an interlocking separable fastener is employed.
- Accordingly, as shown in the accompanying 105 drawing, the edges 18 of the blank 13a are not sewed together, but are sewed to the companion parts of a separable interlocking fastener 19 which are caused to move into interlocking arrangement by a sliding actuator 20 when the latter is drawn upwardly, and to cause the edges 18 to be sep-

arable when slid downwardly to form a slit or opening 20a through which the foot of the wearer may be introduced to the part 12 of the boot.

The separable fasteners 19 may extend as far 5 down toward the heel 11 as is required to open the boot sufficiently to permit the introduction of the foot of the wearer to the portion 12 of the boot. It may actually extend down to a point 21 very close to the heel 11, as shown, if desired; 10 or it may terminate at the point 22 at the upper end of the heel portion 14, so long as the particular foot for which the article is designed can be inserted into the part 12 with convenience, and without making any portion of the boot 15 over-size to suit this convenience.

If desired, the separable fasteners 19 at the rear of the boot may be concealed by a flap 23 formed integral with the part 13, or of a separate piece, and in such cases the flap 23 may be 20 secured to the opposite side of the slit 20a by snap fastener elements 24—25.

To avoid chafing of the wearer's heel and the back of his ankle, a flexible tongue 26a (Fig. 5) may be secured within the heel portion 14 so as 25 to extend over the parts of the foot or ankle which might be chafed by direct engagement with the separable fasteners 19.

The present invention also embraces the provision of such arrangements for puttees and is 30 not in all its aspects limited to a boot. A puttee constructed in accordance with the present invention is illustrated in Fig. 7, and in this case it is preferable that the upper portion 15a be made complete, that is, be unslit, and constitute 35 the terminal position of the operating member 20 of the separable fastener elements 19.

In this case, the ankle portion 17 is reduced in size to fit the ankle of the wearer, and to 40 apply the puttee, the operating member 20 of the separable fastener is slid upwardly to form a slit 20a open at the bottom 26. The size of the opening of the upper portion 15a is sufficient to permit the shoe-clad foot of the wearer to be 45 inserted therethrough, and for convenience, the

foot might be inserted with the toe directed toward the slit 20a after which the puttee, before being closed by the separable fastener, may be rotated on the leg of the wearer to proper position, with the slit and separable fasteners at 80 the rear of the leg.

Variations and modifications may be made within the scope of this invention and portions of the improvements may be used without others.

Having thus described the invention, what is 85 claimed as new and for which it is desired to obtain Letters Patent, is:—

1. An article of foot wear comprising a foot-receiving part, a leg-encircling part connected thereto fully open up the back for substantially 90 its entire length, said leg-encircling portion made of two plies of leather, an intermediate ply of resilient rubber between the two plies of leather of the leg-encircling part and extending slightly beyond the ends of the leather where it forms the opening up the back, and separable fastening means for closing the open portion of the leg-encircling part, located on the outer ends of the resilient rubber and free of the ends of the leather to make the leg-encircling part form-fitting and to compensate for slight changes in 100 the leg of a user.

2. A half boot of leather having a foot-portion; a leg portion shaped to substantially fit the 105 ankle and the calf of the wearer, said leg portion having a vertical slit at the back completely parting the leg portion at the top and extending from the top thereof to at least as far down as the top of the counter on the foot portion to 110 permit the insertion of the foot and leg of the wearer into the boot by a substantially horizontal motion; and a slide operated separable fastening device secured to the margins of the leg portion adjacent said slit to bring and hold the 115 edges of the slit together in substantially abutting relation, the opening at the top of the boot being so small as to prevent withdrawal of the calf and foot without opening said slit.
